The ornamental design for a corrosion control facility, as shown and described.

DESCRIPTION

FIG. 1 is a top perspective view of a corrosion control facility incorporating our new design;

FIG. 2 is a rear perspective view thereof;

FIG. 3 is a bottom perspective view thereof;

FIG. 4 is a top plan view thereof;

FIG. 5 is a bottom plan view thereof;

FIG. 6 is a left side view thereof;

FIG. 7 is a right side view thereof;

FIG. 8 is a front view thereof; and,

FIG. 9 is a rear view thereof.

The broken lines shown in the drawings illustrate portions of the corrosion control facility that form no part of the claimed invention.
